US00D907200S

(12) **United States Design Patent** (10) Patent No.: **US D907,200 S**
Baril et al. (45) Date of Patent: **** Jan. 5, 2021**

(54) **LIGATION CLIP**(71) Applicant: **Covidien LP**, Mansfield, MA (US)(72) Inventors: **Jacob C. Baril**, Norwalk, CT (US);
Justin Thomas, New Haven, CT (US);
Roy J. Pilletere, North Haven, CT (US);
Matthew A. Dinino, Newington, CT (US)(73) Assignee: **Covidien LP**, Mansfield, MA (US)(***) Term: **15 Years**(21) Appl. No.: **29/700,698**(22) Filed: **Aug. 5, 2019**(51) LOC (13) Cl. **24-02**

(52) U.S. Cl.

USPC ..... **D24/128**(58) **Field of Classification Search**

USPC ..... D8/71-74, 394-399, 59; 248/63, 72, 248/74.1, 689, 124.2; 81/487, 385, 386, 81/388-390, 269/3, 4, 6, 143, 165, 240, 269/243, 246-249, 254 R, 147-149; 29/256, 257, 276; 408/103, 104-109; D24/128, 133, 143, 129, 135

CPC A61B 17/122; A61B 17/1227; A61B 2017/00526; A61B 17/1222

(57) **CLAIM**

The ornamental design for a ligation clip, as shown and described.

DESCRIPTION

FIG. 1 is a side perspective view of the ligation clip in accordance with an exemplary embodiment of the design; FIG. 2 is a right side view of the ligation clip shown in FIG. 1;

FIG. 3 is a bottom view of the ligation clip shown in FIG. 1;

FIG. 4 is a top view of the ligation clip shown in FIG. 1; FIG. 5 is a left side view of the ligation clip shown in FIG. 1;

FIG. 6 is a front view of the ligation clip shown in FIG. 1; and,

FIG. 7 is a rear view of the ligation clip shown in FIG. 1.
